UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF ILLINOIS.

STEAM-TURBINE GOVERNOR.

Application filed April 10, 1924. Serial No. 705,466.

This invention relates to steam turbine governors, and particularly to a turbine governor which is assembled as a unit and which may be attached to and detached from and removed from the rotating parts of a fluid turbine, as a unit, without the disturbance of any of the remaining parts of the turbine. Another object is to provide a governor of the described type which may be adjusted for a certain or predetermined rotative speed before it is attached to the turbine. Another object is to provide a complete governor unit which may be inserted into the hollow end of a turbine shaft. Other objects will appear from time to time in the course of the specification and claims.

I illustrate the invention more or less diagrammatically in the accompanying drawings, wherein—

20 Figure 1 is an axial section;

Figure 2 is a view of the governor sleeve with parts in section;

Figure 3 is a view of the governor plunger, and

25 Figure 4 is a detail.

Like parts are indicated by like symbols throughout the specification and drawings.

I do not herein describe or show the details of the turbine beyond indicating the parts in actual contact with the governor assembly herein described and claimed, and it will be understood that the entire turbine assembly is surrounded by the usual housing, not herein shown.

35 A is any suitable turbine shaft rotated by motor means not herein shown, terminating in a hollow portion A¹, opposite the end of the shaft which connects with the motor means, which is externally screwthreaded as at A² to receive the hub A³ of the wheel or rotor A⁴ of the turbine, upon which are mounted any suitable buckets A⁵ adapted to receive the impact of jets of steam directed there against by any suitable mechanism, and to convert the impact of the steam into a rotary movement of the rotor A⁴ and the shaft A.

40 The hollow end of the shaft is interiorly screwthreaded as at B, to receive the screwthreaded portion B¹ of the governor sleeve B². Secured to the outer end of such sleeve or integral with it is the governor collar B³, in the interior of which is mounted a hardened steel collar B⁴. The governor

55 sleeve continues beyond the collar B³, terminating in the hollow, open-ended extension B⁵. The body of the sleeve is slotted as at B⁶, the purpose of the slots being later indicated.

60 Mounted for axial movement within the sleeve B² is a governor plunger comprising a hollow cylindrical portion C, to one end of which is pinned, as by the transverse pin C¹, the inwardly penetrating, cylindrical portion C² of the thrust collar C³, which is 65 of somewhat greater diameter than the governor sleeve. Engaging its outer periphery, or if desired integral with it, is a surrounding sleeve C⁴, the inner edge of which is contacted by the toes D of the governor weights 70 D¹, which are pivoted upon the knife edge portions D² which contact ledges D³ in the collar B⁴ and which are positioned on said ledges, for example by the pins D⁴.

75 E is a collar of carbon or other suitable material which requires no lubrication or is self-lubricating, and is engaged by the thrust collar C³. It is mounted, for example, in the carrier E¹, which in turn is secured to the arm E² pivoted about the bearing element E³ which is held, by any suitable means, against movement in relation to the shaft and rotor. The collar E is provided with a lever extension E⁴ extending to any suitable governor valve, not herein illustrated and not forming part of the present invention, but which is adapted to increase or diminish the flow of motive fluid, in response to the thrust of the collar C³ against the carbon ring, and thus in response to the speed of 80 rotation of the turbine shaft and generator.

85 Projecting inwardly from the opposite end of the governor plunger C is a screwthreaded extension G, of substantially smaller diameter, which is in screwthreaded relation with the governor spring nut G¹, which is itself screwthreaded into the end of the coiled tension governor spring G², the opposite end of which is in screwthreaded relation with the governor spring support G³, the peripheral flange G⁴ of which engages the inner edge of the governor sleeve B². The governor spring nut G¹ is axially adjustable along the screwthreaded extension G, in response to rotation of the governor plunger C, but is itself held against rotation, for example by the lugs or screws G¹⁰, which project outwardly into the slots B⁶.

The thrust collar C³ is provided with an extension C¹⁰, which may be notched or channeled as at C² to receive the end of a screw-driver or may be shaped or socketed in any suitable manner to permit its rotation by any suitable tool.

It will be realized that while I have illustrated herein a working device, and one which is fully operative, nevertheless many changes might be made in the size, shape, number and disposition of parts without departing from the spirit of my invention, and that I wish my description and drawings to be taken as in a broad sense illustrative and not as a limitation to the specific form and details shown.

The use and operation of my invention are as follows:

In fluid turbines, and particularly in steam turbines for use with steam locomotives to operate electric head lights, a very careful regulation or governing of the speed of rotation is necessary in order that the light beam of the head light may be of uniform intensity and of high power. Turbines of this class are exposed to hard usage and are located on an almost constantly moving and highly vibrating base, and yet must operate with the greatest exactness and efficiency, so that when repairs to the governing mechanism are necessary it is important that they be made quickly and easily, and quick and easy regulation of the governing apparatus is vital. I have shown a peculiarly simple and efficient governing mechanism which is detachable as a unit from the turbine, which may be adjusted before being applied to the turbine, and which may easily be adjusted while applied to the turbine. Such a governing mechanism is peculiarly efficient for the railroad work for which it has been developed.

The entire governor assembly may be removed simply by unscrewing the sleeve B² from the hollow of the turbine shaft and removing the whole governor assembly bodily from the shaft. The tension of the governor spring may be adjusted before the assembly is inserted into the turbine, and it may also be adjusted after such insertion, since the carbon ring carrier E¹ is centrally apertured to permit the access of a screw driver or other instrument to the extension C¹⁰ of the thrust collar C³.

I claim:

1. In a governor for fluid turbines, a hollow ended turbine shaft, a governor assembly mounted as a unit therein, and removable as a unit therefrom, comprising a governor sleeve, a governor plunger axially movable therein, a governor collar mounted upon said sleeve, governor weights pivoted in said collar, a thrust connection between the governor weights and the plunger, a governor spring mounted within the gov-

ernor sleeve, and a connection between said spring and the governing plunger.

2. In a governor for fluid turbines, a hollow ended turbine shaft, a governor assembly mounted as a unit therein, and removable as a unit therefrom, comprising a governor sleeve, a governor plunger axially movable therein, a governor collar mounted upon said sleeve, governor weights pivoted in said collar, a thrust connection between the governor weights and the plunger, a governor spring mounted within the governor sleeve adapted to exert tension upon said plunger, and means for adjusting such tension.

3. In a governor for fluid turbines, a hollow ended turbine shaft, a governor sleeve penetrating said hollow end, a governor plunger axially movable therein, a governor collar mounted upon said sleeve, governor weights pivoted in said collar, a thrust connection between the governor weights and the plunger, a governor spring mounted within the governor sleeve, and a connection between said spring and the governor plunger.

4. In a governor for fluid turbines, a hollow ended turbine shaft, a governor sleeve penetrating said shaft, a governor plunger axially movable therein, a governor collar mounted upon said sleeve, governor weights pivoted in said collar, a thrust connection between the weights and the plunger, a coiled tension spring secured at one end to said sleeve and at the other end to said plunger.

5. In a governor for fluid turbines, a hollow ended turbine shaft, a governor sleeve penetrating said shaft, a governor plunger axially movable therein, a governor collar mounted upon said sleeve, governor weights pivoted in said collar, a thrust connection between the weights and the plunger, a coiled tension spring secured at one end to said sleeve and at the other end to said plunger, and means for adjusting the tension of the spring.

6. In a governor for fluid turbines, a hollow ended turbine shaft, a governor sleeve penetrating said shaft, a governor plunger axially movable therein, a governor collar mounted upon said sleeve, governor weights pivoted in said collar, a thrust connection between the weights and the plunger, a coiled tension spring secured at one end to said sleeve and at the other end to said plunger, and means for adjusting the tension of the spring comprising an extension from said plunger, an element axially adjustable along said extension, and a constant connection between said adjustable element and the governor spring.

7. In a governor for fluid turbines, a hollow ended turbine shaft, a governor sleeve penetrating said shaft, a governor plunger axially movable therein, a governor collar

5 mounted upon said sleeve, governor weights pivoted in said collar, a thrust connection between the weights and the plunger, a coiled tension spring secured at one end to said sleeve and at the other end to said plunger, and means for adjusting the tension of the spring comprising a screwthreaded extension from said plunger, a screwthreaded collar mounted thereon, a connection between said collar and said spring, and means for imparting relative rotation to said plunger and collar to move them axially in relation to each other.

10 8. In a governor for fluid turbines, a hollow ended turbine shaft, a governor sleeve penetrating said shaft, a governor plunger axially movable therein, a governor collar mounted upon said sleeve, governor weights pivoted in said collar, a thrust connection 15 between the weights and the plunger, a coiled tension spring secured at one end to

said sleeve and at the other end to said plunger, and means for adjusting the tension of the spring comprising a screwthreaded extension from said plunger, a screwthreaded collar mounted thereon, a connection between said collar and said spring, means for preventing rotation of said collar, and means for rotating said plunger.

15 9. In a governor for fluid turbines, a hollow ended turbine shaft, a governor assembly, mounted as a unit therein and axially removable as a unit therefrom, including a governor sleeve positioned in the hollow of the turbine shaft, a governor plunger axially 20 movable therein, a governor spring mounted within such sleeve, and centrifugal means operative against said governor plunger in response to rotation of the shaft.

Signed at Chicago county of Cook and 25 State of Illinois, this 7th day of April 1924.

CHARLES W. DAKE.
